UNITED STATES PATENT OFFICE.

WILLIAM H. BARTEN, OF ALLEN, SOUTH DAKOTA.

DESIGN FOR A BOLSTER-STAKE.

SPECIFICATION forming part of Design No. 32,296, dated February 27, 1900.

Application filed January 24, 1900. Serial No. 2,688. Term of patent 14 years.

To all whom it may concern:

Be it known that I, WILLIAM H. BARTEN, a citizen of the United States, residing at Allen, in the county of Washabaugh and State 5 of South Dakota, have invented and produced a new and useful Design for Bolster-Stakes, of which the following is a specification.

My invention relates to designs for bolster-stakes, of which the following is a specification, reference being had to the accompanying drawings, forming part thereof, in which—

Figure 1 is a perspective view of a bolster-stake embodying my design. Fig. 2 is a side elevation of the same. Fig. 3 is a top plan view thereof. Fig. 4 is a cross sectional view on the line 4 4 of Fig. 2.

My design consists of the standard A, having the two diverging lower ends B, having 20 the inwardly-extending arms C, constituting

two approximately L-shaped lower ends and the outwardly-extending loops or rings D, situated above the diverging lower ends B.

The essential features of my design are the standard A, with the outwardly-projecting 25 rings or loops D, and the two downwardly-diverging approximately L-shaped lower portions B and C.

Having thus described my invention, what I claim, and desire to secure by Letters Patent, is—

The design for a bolster-stake substantially as herein shown and described.

In testimony whereof I have hereunto set my hand in the presence of two subscribing 35 witnesses.

WILLIAM H. BARTEN.

Witnesses:

LOUIS L. MEEKER,
PHILLIPS WHITE.
